UNITED STATES PATENT OFFICE.

HUGO COOK, OF DAYTON, OHIO.

MOTOR.

1,193,996.

Specification of Letters Patent. Patented Aug. 8, 1916.

Application filed November 3, 1910. Serial No. 590,484.

To all whom it may concern:

Be it known that I, Hugo Cook, a citizen of the United States, residing at Dayton, in the county of Montgomery and State of Ohio, have invented certain new and useful Improvements in Motors, of which the following is a specification.

My invention relates more particularly to motors of the internal combustion type, though as will be seen from the following detailed description, certain features of my invention are broadly applicable to motors of other types. Other features, however, are limited in their application to internal combustion engines.

My invention is illustrated in the accompanying drawings in which—

Figure 1 is a longitudinal section on the offset line 1—1, Fig. 2; Fig. 2 is an end elevation of the machine with the cover plate removed for the purpose of showing the interior mechanism; Fig. 3 is a section on the line 3—3, Fig. 1; Fig. 4 is a section on the offset line 4—4, Fig. 1, looking in the direction of the arrows; Fig. 5 is a section on the line 5—5, Fig. 1, also looking in the direction of the arrows; Fig. 6 is a section on the line 6—6, Fig. 1, the view being taken in the direction of the arrows; Fig. 7 is an elevation of a detail; Fig. 8 is a section on the line 8—8, Fig. 7, viewed in the direction of the arrows; Fig. 9 is a diagram.

The machine shown in Figs. 1 to 8 inclusive of the drawings and to be now described is my preferred embodiment of my invention, but it will be readily apparent that numerous changes, some of which are shown in the drawings and will be described later, can be made therein which will be within the scope of the claims which define the limits of my invention. The motor includes a number of units surrounding and successively acting upon a common shaft and rotating the latter, the means by which motion is communicated from the units to the shaft being one of the novel features of the engine. The casing for the motor is formed of two cylindrical sections, one of which is a closed drum or jacket 9 and contains the cylinders 10 and the other parts of the explosion engines, and the other section, of like diameter, is halved longitudinally, the upper half being removable for easy access to the operating parts and the lower half 11 forming a support for a fly wheel 12 and the

intermediate mechanism by which the energy of the explosion engines is transmitted to the shaft 13. The section 11 may be supported by suitable lugs 14, 14, shown more especially in Figs. 4 and 5, adapted to engage and be secured to a frame, members of which extend on opposite sides of the engine though the supporting means will be modified to suit the particular situation in which the motor is used. The drum 9 and cylinder 11 are provided with flanges 15, 16, whereby they are bolted together as at 17. The cylinders 10 are arranged at uniform intervals in a series concentric with the cylindrical section 9 and may be and preferably are cast integral therewith. The section 9 is further formed with a central axial bore or chamber 18 which receives the reduced end 13' of the shaft 13 which is provided with a main bearing 19 mounted in an annular flange 20 projecting from the inner face of the drum 9 and a secondary bearing 21 mounted in the bore 18 at its outer end. The other end of the shaft 13 which carries the fly wheel is mounted in bearings 22 supported in a sleeve 23 which in turn is received in a cylindrical cavity in a bridge piece 24 cast integral with the lower half 11 of the casing and spanning the open side thereof. The chamber in the bridge piece 24 is formed with an inwardly directed flange 25 at its outer end against which the sleeve 23 abuts and an end thrust bearing 26 is likewise inserted in the sleeve 23 and receives the end thrust from the disk 90 or head 27 of the shaft.

Between the end portions which have been described the shaft is provided with an eccentric portion comprising an inclined bearing shaft 28 and crank portions 29, 30, at 95 either end thereof connecting the inclined bearing shaft with the axial portions of the shaft. The shaft may be made integral from end to end including both axial portions and eccentric portions if desired, but I have shown the cranks integral with the end portions of the shaft and the inclined section integral with crank 29 and connected to crank 30 by a driving fit and secured by a pin 31. It will be clear that when the shaft is revolved each end of the inclined portion will have revolving movement about the axis of the shaft.

Upon the inclined section of the shaft is mounted a sleeve 32 having at one end a 110

lateral thrust roller bearing 33 and at the other both a lateral thrust bearing 34 and an end thrust bearing 35, these bearings being contained in enlargements 36, 37, 38 formed on the sleeve for this purpose. A spider or head 38 is also formed integral with or secured to the sleeve 32 near the middle of its length and with cylindrical openings or recesses 39 corresponding in number to the number of the motor units, there being in this case five such units. On its face remote from the engines the spider is formed or provided with an annular crown gear 40 (see Figs. 1 and 4) concentric therewith and with the inclined shaft section 28 and said gear engages a stationary crown gear 41 (see Fig. 6) mounted upon a strut or bridge member 42 of the half cylinder 11, the engagement of the gears being for the purpose of preventing rotation of the spider. Each motor cylinder is provided with a piston 43 which may be of any usual or approved type, to which is connected by a ball and socket joint a piston rod 44 the other end of which is connected to an arm of the spider by another ball and socket joint, the socket 45 of which is fitted within a recess 39 above referred to and there retained by a screw sleeve 46. It is to be noted that the socket 39 is substantially in axial alignment with the corresponding cylinder 10 and in its movement varies from such axial line but slightly, so that the thrust of the motor element is transmitted and received in a substantially axial line. It therefore follows that no lateral thrust is developed in the cylinder whereby it is worn eccentrically. As a further provision against uneven wear the ball and socket joint freely permits the rotation of the piston in its cylinder so that the piston itself is not worn more upon one portion of its surface than another and in order to aid this rotation an eccentric wing 47 may be provided upon the face of the piston; the operation of which, under the impact of the gases of explosion, being obvious. The section 9 which supports the motor units constitutes a drum or jacket through the head 9^a of which the cylinders 10 extend. The inner end of each cylinder is closed by an end wall 10' provided with a pair of openings for the inlet of combustible gases and the outlet of products of combustion respectively, and between this end wall 10' and the adjacent head 9^b of the drum extend chambers or pockets 52, 53, which surround the inlet and outlet openings respectively and house the valve cages 55, 55'. The valve cages each comprise a valve seat 54, 54', fitting within an opening in the cylinders and is secured in place by a screw-threaded annulus or collar 56, 56', screwing into the valve chambers and surrounding the sleeve 57 in which the valve stems 58, 58', work,

Both valves open inwardly, that is to say, against the pressure in the cylinder, and are normally held closed by means of springs 60, 61, surrounding the valve stems and bearing against the annuli or disks 62 provided on the outer ends of the valve stems for that purpose. All the valves are operated from the main shaft, the reduced end of which extends beyond the drum 9 and carries a worm 63 splined or otherwise secured thereon. For each engine unit there is provided a counter-shaft 64, see Figs. 2, 7 and 8, each mounted in a suitable bracket 65 upon the drum head and carrying a worm gear 66 which engages the worm on the main shaft. Each bracket 65 is formed with an inclined arm 67 which is perforated and carries a stub shaft 68 upon which are journaled at opposite sides of the bracket tappet levers 69, 70, for operating the valves. For this purpose one end of each lever extends over the disk on the end of the valve stem to be operated and the other end is provided with a roller which lies within the path of a cam or tappet 71, 72, formed upon the co-operating counter-shaft 64. It will be understood that the cams 71, 72, are so arranged on their shafts as to operate the inlet and outlet valves respectively at the proper time in the operation of each engine. The worm gears 66 are all inclosed within a split housing 73 which is in the form of an annular casting surrounding the space about the worm 63 and provided with pockets or chambers 74 which receive the worm gears 100 and with which communicate bores 75 which receive the counter-shafts. As heretofore stated, the casting which forms the housing is split, that is to say, formed in two sections, the plane of section running through the axes of the worm gears and shafts and the sections are secured together and to the drum head by bolts or other suitable means not shown. In Fig. 2, however, for the sake of clearness the casing is shown with the outer section removed and the bolt holes are indicated at 76.

An important feature of my invention is found in the conduits for the supply of combustible mixture and exhaust of the products of combustion, which feature is illustrated more especially in Figs. 1 and 3. The main supply conduit is shown at 77, Fig. 3, and extends from and through the outer shell of the drum 9 inward toward the center and near the inner head 9^a thereof to a point close to the wall of the shaft chamber 18. The supply duct is here branched as at 79, the branches extending on opposite sides of the chamber. There being five engine units to be supplied with combustible gas, three of them are connected to one branch by the conduits 80, 81, 82, and two to the other branch by conduits 83, 84. All the conduits 80, 81, 82, converge to a common 130

point, as do the conduits 83 and 84 and each conduit extends directly from the common meeting point to the valve chamber of the engine which it is designed to feed. It will be noted that by this arrangement of conduits, in which the common branching points are near one head of the drum and the points where they open into the valve chambers are near the other head of the drum, the distance of travel of the gas to each engine is substantially the same as the distance of travel to any other engine whereby the gas is supplied to each cylinder under substantially the same conditions of pressure, etc. The exhaust of products of combustion from the cylinders takes place through conduits 85, 86, which are shown in section in Fig. 3. These conduits extend from a common outlet 87 in opposite directions around but within the drum, the contour of which is suitably modified opposite the chambers for the exhaust valves to provide for the conduits, which latter communicate with the exhaust valve chambers 25 through openings in the sides thereof. The inlet conduits and the conduits for products of combustion as well as the engine cylinders are cast in one piece with the drum and the latter is provided with an inlet 88 for cooling water at the bottom and an outlet 89 at the top. The water is heated by the cylinders and exhaust conduits which it cools and in turn transmits the heat to the combustible gases on their way to the engines so that 30 the fuel is suitably and evenly heated before it reaches the engines in which it is to be used. The tappet ends of the valve stem and other parts projecting beyond the head of the drum are inclosed by an annulus 89' 35 and a cover plate 90 secured thereto, the annulus being bolted to the drum head. The openings for the firing plugs are indicated at 99, Figs. 2 and 3, but the firing plugs and their connections are not shown since they 40 may be of any usual or approved type and form no part of the present invention.

An understanding of the operation of my engine may be aided by reference to the diagram in Fig. 9 in which for the sake of simplicity the action of but a single motor unit on the main shaft is shown but that of the entire series of motor units may be readily understood therefrom. In said figure the position of the parts at the beginning of the down-stroke of the piston is shown in full lines and that at the end of the stroke in dotted lines. The main shaft is shown at A' with the inclined eccentric bearing portion thereof at B connected to the parts A, A', by the elbows or cranks C C'. The spider is shown at D, though only the arm connected to the single motor under consideration enters into the operation as described below. It is to be borne in mind that when the shaft rotates the inclined portion B gy-

rates or rotates with a wobbling motion. The spider D, while held from rotation by intermeshing racks 40, 41, partakes of the wobbling motion and each radial element thereof, such as that to which the piston 70 of the motor shown is connected, swings back and forth upon the center of gyration of the inclined shaft B from the position shown in full lines to that represented in dotted lines. We may suppose the shaft B 75 to have moved just past the position of dead center shown in full lines and the explosion of the charge to have taken place. The piston, through its rod, communicates pressure to the arm D of the spider which therefore 80 tends to swing away from the motor about the point X of the shaft B in the direction of the arrow. This it cannot do, however, without being followed by its integral bearing sleeve d'. The latter, however, must be 85 accompanied by the inclined shaft B, which in turn is limited to a motion of gyration as above described about the axis of the shaft A A' and center X. Therefore though the arm D swings directly away from the cylinder without any lateral motion under the impulse given to it by the piston, the inclined shaft B cannot follow in the same plane but swings or gyrates around the axis of the shaft A' and center of gyration X 90 until the parts reach the dotted line position. The gyration of the shaft B is of course accompanied by rotation thereof within the sleeve or bearing d' and accomplishes a partial rotation of the shaft A. 100 Before, however, the rotation due to the first engine or motor unit is accomplished, another motor comes into operation to continue rotation of the shaft and by suitable timing of the ignition of the charges of the 105 several motors each is brought into action before its predecessor ceases to be effective. If, however, the motors are of the four cycle type, to which this invention is particularly adapted, there must be, as is well known, a 110 non-working stroke following each working stroke.

I have found that it is desirable for a reason which will appear, to use an uneven number or odd number of cylinders, the 115 number here shown as before stated being five. In order to provide for the non-working stroke ignition of charge is effected in alternate cylinders successively, the intermediate cylinders taking their charges successively. If the cylinders be numbered in order, 1, 2, 3, 4, 5, the ignition of the charge in cylinder 1 and the corresponding movement of its piston is followed in order by a charging stroke in cylinder 2, a working 120 stroke in cylinder 3, a charging stroke in cylinder 4, a working stroke in cylinder 5, a charging stroke in cylinder 1, a working stroke in cylinder 2, and so on. Since the 125 motors are equidistant around the shaft and 130

hence 72° apart, the impulses in the alternate cylinders are 144° apart. The stroke of each cylinder is effective theoretically through 180° and practically through nearly 5 that arc, so that it will be seen that before the stroke of the first motor ceases to be effective the impulse of the third motor is given to the spider and so on, there being 10 no point in the rotation of the shaft in which it is not subject to the drive of a motor.

Many of the advantages of my construction will be at once apparent to engineers familiar with multiple-cylinder gas engines. 15 The compact arrangement of cylinders around the working shaft gives simplicity in design, a low center of gravity, thereby reducing vibration, and enables the motor to be readily covered in to protect it against 20 dirt and accident. Also it renders the parts easy of access for adjustment and manipulation, it only being necessary to remove the cover plate 90 to get at the valve mechanism of all the cylinders and by a removal 25 of the semi-cylindrical cover 11' the transmission mechanism is readily accessible. As heretofore stated, the cylinders, fuel feed pipes and exhaust conduits may be cast integral with the surrounding drum or cooling 30 jacket and by the arrangement of the conduits in a single casing a preliminary heating of the fuel gas is obtained, which heating is equalized by reason of the approximately equal paths which the fuel gas must 35 travel to the various cylinders. Further, by my construction any odd number of cylinders may be employed with a working shaft having but a single crank, while at the same time the latter is continuously and uninterruptedly driven. By reason of the movement of the pitman and ball and socket connection, irregular wear is avoided as heretofore pointed out and great flexibility is af- 40

flicted and by reason of the direction in which the impulse is given vibration and 45 spring in the crank, which is so marked in engines where the thrust is in a plane transverse to the crank, are largely avoided.

My invention is not limited to the specific construction shown as modifications thereof 50 may be made within wide limits without departing from the scope of my invention.

What I claim is:

1. In a device of the class described, the combination of a rotary shaft having coaxial 55 end sections and an inclined intermediate section, crank arms connecting said intermediate section with the respective end sections, a series of motors arranged about and substantially parallel to said shaft, a lever 60 member rotatably mounted upon the intermediate section of the shaft, a concentric rack upon the lever member, a stationary annular rack with which the concentric rack 65 upon the lever member engages and connections between the motors and the lever member.

2. In a device of the class described, a rotary shaft comprising end bearing portions and an intermediate inclined portion, arms 70 connecting the ends of the inclined portions to the respective end bearings, a spider mounted midway between the ends of the inclined portion of the shaft and sleeve thereon, end bearings between said sleeve and the 75 shaft, a thrust bearing at one end of said sleeve and between the same and the adjacent arm, a stationary annular rack, a rack formed upon the spider and engaging said stationary rack, a series of motors arranged 80 about and substantially parallel to said shaft and connected to said spider.

HUGO COOK.
